AUTOMATIC REVERSIBLE ELECTRIC
SWITCH

Otto Kessler, Bridgeport, Conn.

Application February 24, 1934, Serial No. 712,740

3 Claims. (Cl. 200—47)

This invention relates to automatic reversible electric switches adapted for use in connection with various types of rotary machines, such as rotary electric furnaces, laundry tubs and the like, wherein the carrying member or container of such machines may be rotated or rocked backward and forward variable distances, in a way to agitate or keep in motion the contents of the container.

10 The purpose of my invention is to provide a switch that may be operatively connected to a rotatable electric furnace, laundry tub, or the like, and which in turn will serve to cut out and turn on the current to the motor operating the furnace, and so that the furnace will be automatically reversed at pre-determined times in its 15 rotary movements.

It is also an object of the invention to provide 20 means whereby the amount of rock or throw of the cylindrical furnace may be increased or decreased from time to time, as is usually desirable, as for instance it is customary to start such furnaces by imparting thereto comparatively short 25 rocking movements and to increase their distance of travel from time to time over a period of perhaps fifteen or twenty minutes, the approximate time ordinarily required to melt a charge of brass.

The invention is fully disclosed in an accompanying embodiment thereof, comprising drawings and specification, and as will more fully appear, reference being had to the characters of reference used throughout the specification and found upon like parts of the drawings, in which

35 Fig. 1 shows a top plan view of my novel automatic electric reversing switch;

Fig. 2 is a longitudinal sectional view of the same, taken on line 2—2 of Fig. 1;

40 Fig. 3 shows a cross section taken on line 3—3 of Fig. 1;

Fig. 4 is an end view of a commercial type of 45 rotary electric furnace having one of my electric switches mounted thereon and connected to be operated thereby; and

45 Fig. 5 is a detailed view showing an assembly of rocker shaft 42, arm 40 and collar 48 including its adjusting screw.

I will first refer to Fig. 4 of the drawings wherein is shown an end view of a modern type of 50 rotary electric furnace to which my improved switch is shown applied. This furnace, as will be seen, includes a base 11, a cylindrical metal container 12 having a closable opening 13 through which the furnace is charged and the melted metal is poured.

55 Four rollers 14, two of which are carried by each of the shafts 15 and 16 serve to rotatably support the cylindrical container 12 of the furnace, the said cylinder being rocked through its frictional engagements with the rollers on the

shaft 15 that in turn are journaled in the base 11 and connected to be driven by the reversible motor 17 connected with the far end of the shaft 15. In addition to the two rollers mounted on the shaft 16, there is also provided thereon a sprocket 5 wheel 18 which is connected by a sprocket chain 19 with a sprocket wheel 20 on the feed screw 21 of my improved electric switch 22 that is shown supported on a bracket 23 secured to the before mentioned base of the furnace. This switch is 10 connected through a magnetic reversing switch, not shown, with the before mentioned motor 17 so as to properly effect its reverse drive with the action of the switch of the invention.

My reversing switch 22 will be more readily 15 understood with reference to Figs. 1, 2 and 3, where it will be seen that the same comprises a frame including a bed 25 formed of cast metal and two upwardly extended bearing ribs 26, one at each end which serve in part to support the 20 before mentioned feed screw 21 and an adjusting screw 27, the said feed screw being operated through the sprocket and chain connections herefore referred to while the adjusting screw is provided with a handle 28 so as to facilitate an 25 adjustment of parts of the switch.

A suitable block of insulating material 29 is attached on each of the ribs 26 by means of screws 30. These insulating blocks in turn are notched as at 31 to receive current-carrying guide 30 bars 32, 33, 33^a, 34, 35 and 35^a. The bars 32 and 34 are full length bars, whereas the bars 33 and 33^a, and 35 and 35^a, connected by insulations 36, the portions 33 and 35 serving for the electric circuit breakers on support 37 while the shorter 35 end portions are connected with the circuit breakers on support 38.

Upon these bars are mounted two movable supports 37 and 38 which are formed of insulating material and serve to carry electric-circuit 40 closers and openers. The insulative support 38 is movably mounted upon the guide bars and is adapted for short longitudinal movements as in setting it and its contacting means when the switch is being installed, and to properly adapt 45 its action to the required operation of the furnace or other machine, the operation of which it is to control.

From the foregoing it will be seen that my improved switch is operated by the furnace, whose 50 movements it controls through the sprocket and chain connections with the feed screw 21 journaled in the before mentioned ribs 26 of the bed. This feed screw carries a nut 39 backward and forward with its forward and reverse rotations 55 to alternately engage arms 40 and 41 to operate their rocker shafts 42 carrying electric contacting means, as will later be described.

An adjusting screw 43 having its bearing 44 in the insulation block 29 serves for the adjust- 60

ment of the support 38 with which said screw threadably engages. A larger screw 27 which has its bearings in the ribs 26 threadably engages a metal block 45 secured to the underside 5 of the support 37 and whereby the support is adjusted backward and forward upon the bars 32, 33, 34 and 35 toward and from the before mentioned support 38, the said screw 27 being provided with a handle 28 by means of which it is turned for the purpose of adjusting the said support 37.

In the beginning of the melting of a charge of metal, it is first necessary to turn the screw 27 in a way to move the support 37 inward, close to the insulation 36 and against the limit screw 43. This insures, for the beginning of the operation, the shorter rocking movements of the furnace, whereas a further turning of the screw from time to time in the opposite direction will delay the 10 operation of the mercury switches carried by the supports and consequently cause longer rocking movements of the furnace. These latter adjustments are obviously accomplished during the 15 operation of the furnace and are made from time to time to increase the throw as the metal becomes melted.

While the other support 38 is adjustable as by means of the before mentioned screw 43, yet this adjustment is made only when the switch 22 is 20 installed to form a fixed limit of movement of the furnace in one direction, such for instance as would bring the opening 13 of the cylinder and its spout in a position for pouring.

Like bearings 41 are secured to opposite end 25 portions of each of the supports 37 and 38 to mount the rocker shafts 42 which carry upon their outer ends inwardly and downwardly projecting arms 40 and 41 that are engaged by the before mentioned floating nut 39 mounted upon 30 the feed screw 21. These arms are loosely mounted upon their shafts, being normally supported in the position shown in Figs. 2 and 5, by means of a collar 48 secured to the rocker shaft 42 and whereby the shaft will be rocked against the 35 action of a spring 49 mounted on the shaft and having one end secured thereto and the other one secured to the before mentioned bearing.

At this point it might be fitting to state that the two supports 37 and 38 including their rocker 40 shafts and electric contacting mechanisms carried by said shafts are substantially alike in both instances and therefore like characters of reference will be applied to similar parts of the two sets. Upon each shaft 42 are pairs of arms 50—50 45 set at slightly different relative angular positions, and which are provided with transparent tubular liquid-metal containers 51 having suitable contacts 52 whereby when the rocker shafts and arms are in one position an electric contact will be insured whereas when in another position said contacts will be broken and others made. Suitable wire connections *a*, *b*, *c* and *d* are made from the mercury switch contacts to the conducting bars and these in turn having wire connections 55 *e*, *f*, *g*, *h* and *i* with a commercial type of magnetic reversing switch, not shown.

From the foregoing description it will be understood that with the parts in the position shown in Fig. 1, a drive of the feed screw 21 as from 60 the furnace will cause the nut 39 upon the feed screw to be fed forward and engage with the arm 40 or 41 according to the direction of rotation of the feed screw. This engagement will cause the shaft 42 upon which the arm 40 or 41 65 is mounted to be rocked so that the arms 50 on

said shaft would be swung over into a different position so that the liquid metal such as mercury, carried in the transparent tubes mounted in the outer end portions of said arms, would be shifted to reverse the respective electric contacts of the 5 switches. This change of contact is obviously conveyed through the wire connections, guide bars, magnetic reversing switch, etc., to the motor driving the furnace and whereby said motor is reversed and the direction of rotation of the furnace and feed screw 21 are likewise reversed, thereby reversing the travel of the nut 39 to engage the other depending arm upon the other rocker shaft in a manner to operate its electric contacting mechanisms and again reverse 10 the order of rotation.

In this connection it will also be apparent that the nearer the support 37 is positioned to the support 38, the quicker the engagements of the nut 39 with the arms 40 and 41 and consequently 15 a quicker reversal or shorter rocking movement of the furnace. This re-positioning or adjusting of the support 37 during the operation of the furnace, as before stated, is brought about by the operation of a handle 28 and its shaft 27, 20 from time to time, during the melting of the charge of metal in the furnace.

Having thus described my invention, what I claim and desire to secure by Letters Patent is:

1. In an automatic reversible electric switch, a frame, a reversible feed screw, electric conducting guide rods, switch-carrying supports mounted on the rods, separate means for adjusting one support on the rods with respect to the other, a rocker shaft carried on each support, arms upon the shafts, liquid metal contacting means carried by the arms, means for holding the rocker shafts in their normal positions, a floating nut mounted upon the feed screw, a contact arm carried upon each rocker shaft and projected in the line of travel of the said nut for alternately operating the shafts.

2. In an automatic reversible electric switch, a frame, a feed screw, insulating blocks mounted on the frame, electric conducting guide rods 45 mounted in the blocks, insulating supports mounted on the rods, means for adjusting either support on the rods with respect to the other, a rocker shaft carried on each support, arms upon each shaft that are projected at different angles, 50 alternately operable electrical contacting means carried by the arms, means for holding the rocker shafts in their normal positions, a floating nut mounted upon the feed screw, a contact arm carried upon each rocker shaft and projected in the line of travel of the said nut.

3. An automatic reversible electric switch, including a frame, a reversible feed screw, insulating blocks mounted on the frame, electric conducting guide rods mounted in the blocks, switch 60 carrying supports adjustably mounted on the rods, a separate adjusting screw for adjusting one support on the rods with respect to the other while the switch is in use, a rocker shaft carried on each support, a pair of switch arms upon each 65 shaft, electric contacting means carried by each arm, yieldable means for holding the rocker shafts in their normal positions, a floating nut mounted upon the feed screw, contact means carried upon each rocker shaft and projected in the 70 line of travel of said nut for alternately operating the shafts and their electric contacting means and electric wire connections from the contact means to the guide rods.
